[57] CLAIM

The ornamental design for "utensils", as shown and described.

DESCRIPTION

FIG. 1 is a perspective view of a combined assembly of a

knife, a fork and a spoon of the utensils showing our new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a left side view thereof;

FIG. 7 is a right side view thereof;

FIG. 8 is a perspective view of the knife shown separately for ease of illustration;

FIG. 9 is a top plan view thereof;

FIG. 10 is a front elevational view thereof;

FIG. 11 is a bottom plan view thereof;

FIG. 12 is a rear elevational view thereof;

FIG. 13 is a left side view thereof;

FIG. 14 is a right side view thereof;

FIG. 15 is a perspective view of the fork shown separately for ease of illustration;

FIG. 16 is a top plan view thereof;

FIG. 17 is a front elevational view thereof;

FIG. 18 is a bottom plan view thereof;

FIG. 19 is a rear elevational view thereof;

FIG. 20 is a left side view thereof;

FIG. 21 is a right side view thereof;

FIG. 22 is a perspective view of the spoon shown separately for ease of illustration;

FIG. 23 is a top plan view thereof;

FIG. 24 is a front elevational view thereof;

FIG. 25 is a bottom plan view thereof;

FIG. 26 is a rear elevational view thereof;

FIG. 27 is a left side view thereof; and,

FIG. 28 is a right side view thereof.
